UNITED STATES PATENT OFFICE.

BERNARD T. LEVEQUE, OF WENHAM, MASSACHUSETTS, ASSIGNOR TO UNITED SHOE MACHINERY CORPORATION, OF PATERSON, NEW JERSEY, A CORPORATION OF NEW JERSEY.

WORK CLAMP FOR BUTTONHOLE-SEWING MACHINES.

Application filed November 18, 1921. Serial No. 516,183.

To all whom it may concern:

Be it known that I, BERNARD T. LEVEQUE, a citizen of the United States, residing at Wenham, in the county of Essex and State 5 of Massachusetts, have invented certain new and useful Improvements in Work Clamps for Buttonhole-Sewing Machines; and I do hereby declare the following to be a full, clear, and exact description of the invention, 10 such as will enable others skilled in the art to which it appertains to make and use the same.

The invention relates to work holding and 15 thread cutting mechanism for buttonhole sewing machines.

The invention provides simple and efficient 20 mechanism for opening and closing the work engaging jaws of the work clamp, for spreading the jaws to hold the work taut at the point where the buttonhole is made and for actuating the thread cutter with which 25 one of the jaws is provided, and it comprises the features of construction and combination of parts hereinafter described and referred to in the claims.

While not confined in its application to such machine the invention is intended primarily as an improvement in the machine shown and described in application Serial 30 No. 255,849, filed September 26, 1918, and has been shown and will be further explained as applied to this machine.

In the drawings Fig. 1 is a side elevation showing so much of the sewing machine of 35 said patent as is necessary to show the application of the invention thereto, Fig. 2 is a sectional elevation, and Fig. 3 is a plan view of the parts shown in Figs. 1 and 2.

The machine to which the invention has 40 been applied comprises in general a stitch forming mechanism which is mounted to rotate while sewing about the eye and bar end of the buttonhole and which includes an upper needle 2, an under needle 4 and a looper 45 6, a small reciprocating cutter 8 which acts on the work just ahead of the sewing point to progressively cut the buttonhole slit during the sewing, and a work clamp which is movable lengthwise and laterally of the buttonhole and which carries a thread cutter for cutting and holding the upper needle thread 50 at the completion of the buttonhole. The parts of the work clamp are carried on the

clamp carriage which comprises a curved plate 10 carried upon supporting arms one 55 of which, indicated at 12, is mounted to slide and turn on the cam shaft 14. The carriage is moved lengthwise of the buttonhole by a feed cam 16 secured to the cam shaft and provided with a cam groove engaging a roll 60 carried by a lever 18, the upper end of which is connected by a link 20 with the carriage. The carriage is moved laterally by a cam groove formed in a flange 22 on the feed cam which engages a roll on the lever 24. 65 The upper end of the lever is connected by a link 26 with a stud 28 projecting from the carriage. The stud is arranged to slide through the end of the link during the backward and forward movement of the carriage 70 and this end of the link is provided with a vertical projection 30 arranged to move laterally in a fixed guideway 32 on the machine frame.

The means for gripping or clamping the 75 work upon the carriage comprises the work supporting plates 34 and the vertically movable clamping jaws 36 and 38. The plates and jaws are shaped to embrace the path of action of the stitch forming mechanism and 80 the jaws are mounted for relative movement lengthwise of the buttonhole, since it is desirable to hold the work taut in this direction during the progressive cutting of the buttonhole slit. The front jaw 36 is pivotally supported in the arms of a yoke formed on the forward end of the clamp lever 40 while the rear clamping jaw 38 is pivotally supported in the arms of a yoke formed on the forward 85 end of a bar 42 which is mounted to slide in a bearing formed in the lever 40 and is forced yieldingly forward by a spring 44. The forward movement of the bar 42 is limited by a collar 46 secured to the bar and arranged to engage the rear end of the bearing 90 and thus determine the forward or normal position of the jaw 38 with relation to the jaw 36. The hub of the clamp lever 40 fits between two lugs 48 formed on the clamp carriage and the lever is pivotally supported 95 upon two studs 50 which pass through the lugs and enter bearings formed in the end of the hub. The studs are held in position in the lugs by spring pressed latching balls 52 arranged to engage grooves 54 in the studs. 100 The studs may be readily withdrawn from 105

the hub of the clamping lever to permit the removal and replacement of the lever and the parts carried thereby and when withdrawn are held in retracted position by engagement 5 of the latching balls with the grooves 56 in the studs. The clamp lever is provided with a rearwardly projecting arm the rear end of which lies in a clevis formed by two plates 58 and 60 on the upper end of a vertically 10 movable stud 62. The stud is forced upward and thus in a direction to close the clamp and press the clamping jaws 36 and 38 firmly against the work by a spring 64. The means for opening and closing the clamp 15 20 25 30 35 40 45 50 55 60 65 comprises a bell crank lever 66, one arm of which is arranged to engage the upper plate 58 of the stud 62, and the other arm of which carries a roll engaged by a cam 68 which is driven from the cam shaft 14. This construction permits the clamp lever and parts carried thereby to be readily removed and replaced when the parts are held in clamp opening position as indicated in Fig. 1. The mechanism for relatively moving the 25 30 35 40 45 50 55 60 65 jaws 36 and 38 to stretch the work and hold it taut is carried on the clamp lever and is operated from the clamp opening and closing mechanism with which it is so connected as not to interfere with the removal and re- placement of the lever. As shown this mechanism comprises toggle links 70, one of which is pivoted to the hub of the lever 40 and the other of which is pivoted to a collar 72 adjustably held on the end of the bar 42 35 40 45 50 55 60 65 70 75 80 85 90 95 100 105 110 115 120 125 130 by the nuts 74. The toggle is connected by a link 76 with a lever 78 which is pivoted on an arm rising from the lever 40 and is provided at its rear end with a clevis 80 embracing a stud 82 which projects from the side of the clamp closing lever 66. The stud 82 may be in the form of an eccentric sleeve which is secured in adjusted position on a stud 84 by a nut 86. When the horizontal arm of lever 66 is raised to close the clamp 40 45 50 55 60 65 70 75 80 85 90 95 100 105 110 115 120 125 130 135 arm of lever 66 is raised to close the clamp the toggle links 70 and connected lever 78 move with the clamp lever 40 until the jaws 36 and 38 engage the work and then continued upward movement of the lever 66 into the position indicated in Fig. 2 rocks the 45 50 55 60 65 70 75 80 85 90 95 100 105 110 115 120 125 130 135 lever 78 to straighten the toggle links 70 and thus draw the bar 42 and jaw 38 rearward to stretch the work lengthwise of the buttonhole. The movement given to the lever 78 is sufficient to carry the knuckle of the toggle 50 55 60 65 70 75 80 85 90 95 100 105 110 115 120 125 130 135 below the line of centers as indicated in Fig. 2 so that the toggle firmly locks the jaw in its retracted position during the sewing of the buttonhole. When the lever 66 is operated to open the clamp at the completion of the buttonhole the first downward movement of its horizontal arm rocks the lever 78 to break the toggle so that the jaw 38 is returned to its forward position by the spring 44. After the jaw has been thus returned 65 70 75 80 85 90 95 100 105 110 115 120 125 130 135 the continued movement of the lever 66 de-

presses the stud 62 and rocks the lever 40 against the pressure of the spring 64 to open the clamp as indicated in Fig. 1.

The jaw 36 of the work clamp is provided with a thread cutter and holder in the form 70 of a lever 88 arranged to pass between two plates 90 and 92 on the jaw and to cooperate therewith in severing and holding the upper needle thread. The mechanism for actuating the thread cutter and holder is mounted 75 on the clamp lever 40 to be removed and replaced therewith and is actuated from the clamp opening and closing mechanism through the jaw spreading mechanism. As shown the thread cutter and holder is connected by a twisted link 94 with the vertical arm of a three-arm lever 96 which is pivoted on the same pivot which supports the lever 78 and is provided with an arm extending laterally over the front end of this lever and also with an arm extending rearwardly into position to engage the laterally projecting end of the stud 84 on the lever 66. The thread cutting and holding lever 88 is held in open or closed position by a leaf spring 98, the end of which is shaped to engage either one edge or the other of the vertical arm of lever 96.

When the lever 66 is moved at the completion of a buttonhole to return the jaw 38 to forward position and open the clamp the movement of the lever 78 which precedes the opening of the clamp will rock the three-arm lever 96 into the position indicated in Figs. 1 and 3 and thus swing the thread cutting and holding lever 88 across the needle path and into position between the plates 90 and 92, thus severing and holding the upper needle thread just prior to the opening of the clamp. The outer end of the spring 98 will now bear against the rear edge of the vertical arm of the lever 96 and retain the thread cutting and holding lever in this position, when the lever 66 is moved into the position indicated in Fig. 2 to close the clamp and spread the jaws 36 and 38. The lever 88 will, therefore, continue to hold the thread during the sewing of the initial stitches of the buttonhole seam and during the first part of the forward travel of the clamp carriage. The forward movement of the clamp carriage will bring the cam surface 100 on the three-arm lever 96 into engagement with the stud 84 on the arm 66 so that the lever will be rocked to withdraw the thread holding and cutting lever 88 from between the plates 90 and 92 and into position to again act upon the needle thread. The lever will be held in this open position until the completion of the buttonhole and until the lever 66 is again operated to open the clamp, by the engagement of the curved end of the spring 98 with the forward edge of the vertical arm of the three-arm lever 96.

In order that the clamp may be conven-

iently opened manually an eccentric 102 is secured upon a rock shaft 104 and is arranged to engage and lift the forward arm of the clamp lever 40. The rock shaft is 5 mounted in a bearing on the clamp carriage and is provided with an operating handle 106 arranged within convenient reach of the operator.

While it is preferred to employ the specific construction and arrangement of parts shown and described in embodying the invention in the machine of the patent above referred to it will be understood that this construction and arrangement is not essential 10 to the broader features of the invention and may be varied or modified as found desirable or best suited to the construction and mode of operation of the machine in which it is to be embodied.

20 I claim:

1. A work clamp comprising a clamp lever, mechanism for automatically actuating the lever to open and close the clamp, work engaging jaws carried by the lever, 25 and mechanism for spreading the jaws mounted on the lever and operated from the lever actuating mechanism.

2. A work clamp comprising a clamp lever, mechanism for actuating the lever to 30 open and close the clamp, work engaging jaws carried by the lever, a toggle on the lever for spreading the jaws, and means for operating the toggle from the lever actuating mechanism.

3. A work clamp comprising front and 35 rear work engaging jaws, a toggle for spreading the jaws lengthwise of the buttonhole, and mechanism for closing the jaws and then straightening the toggle, and for 40 breaking the toggle and then opening the jaws.

4. A work clamp comprising a clamp lever, a work engaging jaw on the forward end of the lever, a bar mounted to 45 slide in the lever, a work engaging jaw on the forward end of the bar, a toggle connecting the bar and lever, means for straightening the toggle when the jaws are closed and for breaking the toggle when the 50 jaws are raised.

5. A work clamp comprising a clamp lever, work engaging jaws carried on the lever, a spring operated clevis engaging the rear end of the lever, a cam operated lever 55 for depressing the clevis to open the clamp, jaw spreading mechanism including a clevis mounted on the clamp lever, and a stud on the cam lever embraced by the latter clevis.

6. A work clamp comprising a clamp lever, work engaging jaws carried on the lever, a cam operated lever for actuating the 60 clamp lever, jaw spreading mechanism

mounted on the clamp lever, a thread cutter on one of the jaws, connections for actuating the cutter from the jaw spreading 65 mechanism to cut the thread and from the cam lever to release the thread.

7. A traveling work clamp comprising a clamp lever, work engaging jaws carried on the lever, a thread cutter and holder on one 70 of the jaws, mechanism for automatically actuating the lever to open and close the clamp, and mechanism for actuating the cutter and holder mounted on the lever and operated from the lever actuating mechanism to cut and hold the thread and operated during the travel of the clamp to release the thread.

8. A work clamp comprising a clamp lever, work engaging jaws carried on the 80 lever, mechanism for actuating the lever to open and close the clamp, mechanism carried on the lever for spreading the jaws, and a thread cutter on one of the jaws operated 85 from the spreading mechanism.

9. A work clamp comprising a clamp lever, work engaging jaws carried on the lever, mechanism for actuating the lever to open and close the clamp, jaw spreading 90 mechanism on the lever operated by the lever actuating mechanism, and a thread cutter on one of the jaws operated from the spreading mechanism.

10. A work clamp comprising a clamp carriage, a clamp lever on the carriage, work 95 engaging jaws carried on the lever, a cam operated lever for actuating the clamp lever, jaw spreading mechanism on the clamp including a clevis, a stud on the cam lever embraced by the clevis, a thread cutter on one 100 of the jaws, a lever for actuating the thread cutter mounted on the clamp lever and operated to cut the thread by the movement of the clevis preceding the opening of the clamp and operated from the cam lever to retract the cutter during the forward travel of the carriage.

11. A work clamp comprising a clamp lever, work engaging jaws carried on the lever, a clevis embracing the rear end of the lever, a spring for forcing the clevis upward and endwise movable pivot studs for 110 removably engaging bearings in the lever.

12. A traveling work clamp comprising a clamp lever, a thread cutter and holder on the lever, a clamp operating lever, connections through which motion is transmitted from the clamp operating lever to the thread cutter and holder to cut and hold the thread 115 and thereafter release the thread during the travel of the clamp, a rotary cam shaft, and a cam on the shaft for operating the clamp operating lever.

BERNARD T. LEVEQUE
